GEORGE C. MURRAY, OF CHICAGO, ILLINOIS.

DRAWBAR YOKE.

1,418,450.

Specification of Letters Patent. Patented June 6, 1922.

Application filed March 18, 1918. Serial No. 223,086.

To all whom it may concern:

Be it known that I, GEORGE C. MURRAY, a citizen of the United States, residing at Chicago, in the county of Cook and State of Illinois, have invented certain new and useful Improvements in Drawbar Yokes, of which the following is a specification.

This invention relates to a yoke for connecting the draft gear of railway cars with the draw-bar, and the purpose is to provide an improved construction for detachably connecting the draw-bar or coupler and the yoke.

The principal object of the invention is to provide a construction in which the coupler butt is retained within the yoke by means comprising a removable gib, without making holes in the walls of the yoke or employing auxiliary fastening means for the removable gib. Another important object is to provide a construction in which the coupler butt is supported directly upon the lower wall of the yoke, and is retained in the yoke by a fixed flange and a removable gib engaging the shoulders of the butt. A further object is to provide a yoke having a hooded forward end and inwardly directed flanges carried by the upper and lower arms, in combination with a draw-bar having one shoulder adapted to engage directly one of said flanges and another shoulder adapted to engage the gib insertable into the hooded portion from the forward end of the yoke and retained in position by said other flange. Still another object is to provide, in combination with the usual draw-bar, having a shank and a shouldered butt, a yoke having a flange to engage one shoulder of the draw-bar butt and a removable gib adapted to be inserted into the yoke from the forward end thereof between the shank of the coupler butt and a retaining lug carried by the lower wall of the yoke, the space between the lug and shank being such that the gib is insertable only when the coupler butt has been displaced rearwardly in the yoke, in order to bring into position opposite the lug a part of the shank having a reduced vertical dimension, whereby the gib is automatically held in position by the draw-bar when the latter is in its normal forward position. Other objects relate to various features of construction and arrangement which will appear more clearly hereinafter.

The nature of the invention will be understood from the following specification

taken in connection with the accompanying drawings in which two embodiments are illustrated.

In the drawings—

Figure 1 is a side elevation of the draw-bar and yoke with the forward part of the yoke shown in section on the line 1—1 of Fig. 2;

Fig. 2 is a top plan view of the draw-bar and yoke with parts thereof shown in horizontal section;

Fig. 3 is a perspective view of the removable gib;

Fig. 4 is a side view similar to Fig. 1, illustrating the method of inserting the coupler butt into the yoke and the method of inserting the removable gib into the yoke after the coupler butt has been displaced rearwardly;

Fig. 5 is a front elevation of the yoke and draw-bar, with the latter displaced rearwardly in the yoke, showing the removable gib being inserted into the forward end of the yoke;

Fig. 6 is a front elevation similar to Fig. 5 showing the position of the parts after the removable gib block has assumed its normal position, as shown in Fig. 1; and

Fig. 7 shows a side elevation of the forward end of a modified form of yoke.

In the accompanying drawings the yoke is shown as comprising upper and lower arms or straps 10 and 11, respectively, which are connected at their rear ends by the rear wall 12. The arms 10 and 11 are increased in width adjacent their forward ends, as illustrated in Fig. 2, and the forward portions thereof are connected by integrally formed side walls or webs 13, having the form illustrated in Figs. 1 and 2. These side walls, with the upper and lower walls of the yoke, form a hooded enclosure at the forward end of the yoke adapted to receive the shouldered butt 14^a of the coupler butt 14 having the shank 14^b extending forwardly from the shouldered butt, according to the usual form of construction.

The forward end of the upper arm 10 is provided with a depending flange or lug 15 adapted to coact with the upper shoulder 16 of the coupler butt, and the wall of the yoke is reinforced above this flange by a transverse rib 17. When the coupler butt is in its normal forward position, as illustrated in Fig. 1, the lower surface thereof is adapted to contact with the lower wall

11 of the yoke over a considerable area, as shown at 19, and forwardly of these contacting surfaces the lower wall of the yoke is inclined downwardly and forwardly as shown at 11^a. The forward end of this inclined portion 11^a of the lower wall carries an integrally formed upwardly extending lug or flange 20, and at each end of the lug 20 other integral lugs or shoulders 21 extend upwardly adjacent the side walls 13 of the yoke. The flange 20 and the lugs 21 serve as retaining means for a removable gib or block 22, which is insertable into the hooded end of the yoke through the forward opening thereof, and is adapted to coat with the lower shoulder 18 of the coupler butt. The block 22 has the form illustrated particularly in Fig. 3 and is provided with end projection 22^a adapted to lie rearwardly of and in contact with the end lugs 21; the block 22 also has a depending portion 22^b adapted to lie rearwardly of and in contact with the transversely extending flange 20. The lower corners of the gib are cut away, as shown at 22^c, for a purpose to be herein-after described, and the forward side of the block is hollowed out, as shown at 22^d and 22^e, on opposite sides of the forwardly projecting rib 22^f, which serves to strengthen the gib and also to provide a handle by which the same may be inserted into the yoke. The lower inclined wall 11^a of the yoke is provided on its lateral edges with strengthening ribs 23 having upturned lugs 23^a at the forward ends thereof adjacent the gib block 22. Guideways are thus formed between the ribs 23 and the lugs 21 to receive the gib 22 after the same has been inserted into the yoke.

40 In order to insert the draw-bar butt into the yoke, it is necessary to tilt it downwardly, as illustrated by dotted lines in Fig. 4, and the parts of the yoke are so proportioned that when the draw-bar is in this tilted position the butt thereof will pass between the upper flange 15 of the yoke and the lower flange 20 carried by the lower wall, the width of the butt being slightly less than the horizontal distance between the upwardly extending side lugs 21 which are located at the ends of the flange 20. The coupler butt may then be moved rearwardly until the shoulders thereof have cleared the flanges 15 and 20, after which it can be returned to its normal horizontal position, as illustrated by full lines in Fig. 4. When in this latter position, rearwardly of the forward end of the yoke, the portion 14^e of the coupler shank, adjacent the coupler butt, which has the enlarged vertical dimension, is located rearwardly of the side lugs 21, so that sufficient space is then provided between these side lugs and the shank 14^b to permit the end portions 22^a of the gib to pass between the lugs 21 and the shank, and to permit the

body of the block to pass over the lower flange 20. The gib is then passed over the end lug, as illustrated in Fig. 4, and allowed to drop into position behind the lugs 21 and the flange 20, where it is automatically retained in position by virtue of its own weight. However, when the coupler butt is returned to its normal forward position, as illustrated in Fig. 1, the enlarged part 14^e of the shank reduces the spaces between the shank and the lugs 21, so that it is impossible to remove the block when the coupler butt is within its normal range of movement within the yoke. When the coupler butt is moved rearwardly in compressing the draft gear in normal operation, the gib is prevented from tipping rearwardly by the strengthening ribs 23.

The improved yoke herein described is preferably formed of cast steel, and it has a great advantage over yokes heretofore known in that the integral hooded forward end of the yoke is not slotted, cut, or otherwise weakened in order to secure the coupler butt within the yoke. In this invention the removable gib, by which the coupler butt is retained, is located in a position wholly forward of the coupler butt and wholly within the hooded end of the yoke, so that no apertures are made in the side walls, and the lower wall of the hood is not weakened by fastening devices for the gib. By reason of the novel construction which permits the gib to be inserted only when the coupler butt has been displaced rearwardly in the yoke, the gib is automatically held within the hooded end when the coupler butt is in its forward position, or is within its normal range of movement during the compression of the draft gear in actual operation, it being understood that the coupler butt is free to move rearwardly in the yoke on the lower arm by which it is supported. The stresses transmitted to the yoke from the draw-bar are distributed, in this construction, throughout the hooded end of the yoke and not concentrated on the side walls, or any particular part of the yoke construction. Various other advantages will be apparent to those skilled in the art without detailed description herein.

In Fig. 7 I have illustrated a modified construction of the yoke, in which a transverse key is combined with the other features of construction embodied in the form of yoke previously described. This modified yoke, designated generally by the numeral 30, is in all respects similar to the yoke previously described, except that the side wings or walls 31 are increased in dimension longitudinally of the yoke and are provided with longitudinally extending key-holes 32 located in alignment with another key-hole extending through the draw-bar 33 on the longitudinal axis thereof. A key 34

is adapted to be inserted through these alining key-holes, and through the longitudinal sills of the car located on opposite sides of the yoke. In this construction the strain 5 is transmitted from the draw-bar to the yoke partially through the key and partially through the flange and block which engage the upper and lower shoulders of the draw-bar butt.

10 Although I have shown and described certain embodiments of the invention for purposes of illustration, it will be understood that it may be constructed in widely different forms without departing from the scope 15 of the appended claims.

What I claim is:

1. The combination in a draw-bar yoke, of a hooded forward end adapted to receive a shouldered draw-bar butt, means carried 20 by said yoke for engaging one shoulder of said butt, and a removable gib insertable from the forward end of said yoke for engaging the other shoulder of said butt, the lower wall of said yoke being adapted to 25 engage and directly support said butt when the latter is in its normal forward position.

2. The combination in a draw-bar yoke, of a hooded portion at the forward end adapted to receive a shouldered draw-bar 30 butt, the upper wall of said hooded portion carrying a part adapted to engage the upper shoulder of said butt, and a removable gib insertable into the lower part of said hooded portion from the forward end of 35 said yoke to engage the lower shoulder of said butt, the lower wall of said yoke being adapted to engage and directly support said butt when the latter is in its normal forward position.

40 3. The combination in a draw-bar yoke, of a hooded forward end adapted to receive a shouldered draw-bar butt, means carried by said yoke for engaging one shoulder of said butt, and a removable gib insertable 45 into said yoke from the forward end thereof when said butt is moved rearwardly from its normal position, said gib being adapted to engage the other shoulder of said butt when the latter is in its forward position, 50 the lower wall of said yoke being adapted to engage and support said butt.

4. A yoke having upper and lower arms and a hooded forward end, integral shoulders at the forward ends of said upper and 55 lower arms, and a one-piece locking member insertable bodily through the front end of the yoke to engage the shoulder on said lower arm and to cooperate with the shoulder on said upper arm for engaging the 60 shoulders of the coupler butt and retaining the same in said yoke, said locking member being adapted to lie wholly in front of the coupler butt when the same is in its normal position in said yoke.

65 5. The combination in a draw-bar yoke,

of upper and lower arms united at their forward ends by integral side walls forming a hood adapted to receive a shouldered draw-bar butt, means carried by said yoke for engaging one shoulder of said butt, and a movable gib located entirely within said hood between said side walls and automatically held in position to engage the other shoulder of said butt, said gib being insertable bodily 70 from the forward end of said hood, the lower wall of said yoke being adapted to engage and support said butt when the latter is in its forward position.

6. The combination with a yoke having upper and lower arms and a hooded forward end, of a draw-bar provided with a shouldered butt adapted to be received within said hooded end, means carried by said hooded end to prevent insertion of said butt within said yoke except when said draw-bar is tilted downwardly at its forward end, and means comprising a movable member insertable into said hooded end from the forward opening thereof after said butt has been inserted into said yoke for retaining said butt 80 within said yoke.

7. The combination with a yoke having upper and lower arms and a hooded forward end, of a draw-bar having a shouldered butt adapted to be received within said hooded end when the forward end of the draw-bar is tilted in a vertical plane, and means cooperating with the hooded end of said yoke for retaining said butt therein after it has been inserted, said last-named means comprising a movable member insertable into said hooded end through the forward opening thereof only after said coupler butt has been displaced rearwardly in said yoke.

8. The combination in a draw-bar yoke, of a hooded forward end adapted to receive a shouldered draw-bar butt, means carried by said yoke for engaging one shoulder of said butt, and a removable gib insertable from the forward end of said yoke for engaging the other shoulder of said butt, the lower wall of said yoke being adapted to engage and support said butt when the latter is in its normal forward position, said gib being retained wholly within the walls of 105 said hooded forward end.

9. The combination with a yoke having upper and lower arms and a hooded forward end, of a draw-bar having a shouldered butt adapted to be received within said hooded end, inwardly directed flanges carried by the upper and lower walls of said hooded end, one of said flanges being adapted to engage one shoulder of said butt, and a removable gib insertable into said yoke from the forward end thereof and adapted to be automatically held within said hooded end to engage the other shoulder of said butt, the lower wall of said yoke being also adapted 110 to engage and support said butt.

10. The combination with a yoke having upper and lower arms and a hooded forward end, of a draw-bar having a shouldered butt adapted to be received within 5 said hooded end, a flange carried at the forward end of said upper arm to engage the upper shoulder of said butt, lugs carried by the forward end of said lower arm adjacent the side walls of said hooded end, and a removable block supported by said lower arm and insertable into said yoke from the forward end thereof after said butt has been inserted, said block being held in said yoke only by coaction with said lugs and engaging 10 the lower shoulder of said butt.

11. The combination with a yoke having upper and lower arms and a hooded forward end, of a draw-bar having a shouldered butt adapted to be received within 20 said hooded end, a flange carried at the forward end of said upper arm to engage the upper shoulder of said butt, lugs carried by the forward end of said lower arm adjacent the side walls of said hooded end, 25 and a removable block supported by said lower arm and coacting with said lugs to engage the lower shoulder of said butt, said removable block having the lower corners thereof cut away to permit the insertion of 30 said block between the shank of said draw-bar and said lugs after said butt has been inserted in said yoke.

12. The combination with a yoke having upper and lower arms and a hooded forward end, of a draw-bar having a shouldered butt adapted to be received within 35 said hooded end, a flange carried at the forward end of said upper arm to engage the upper shoulder of said butt, lugs carried by 40 the forward end of said lower arm adjacent the side walls of said hooded end, a removable

block supported by said lower arm and coacting with said lugs to engage the lower shoulder of said butt, said removable block having the lower corners thereof cut away 45 to permit the insertion of said block between the shank of said draw-bar and said lugs after said butt has been inserted in said yoke, and a transverse flange extending upwardly from said lower wall to coat 50 with the lower edge of said block after the latter has been inserted.

13. The combination with a yoke having upper and lower arms united at their forward ends with integral side walls forming 55 a hood, of a draw-bar having a shouldered butt and a shank having an increased vertical dimension adjacent said butt, a flange formed integrally with the forward end of said upper wall and extending downwardly 60 therefrom to coat with the upper shoulder of said butt, a transverse flange formed integrally with the forward end of said lower wall and extending upwardly therefrom, lugs formed integrally with said lower wall 65 and with said side walls at the ends of said transverse flange, and extending upwardly above said transverse flange, said lugs being adapted to permit the insertion of said coupler butt between them, and a removable 70 block adapted to be inserted into said hood after said butt has been inserted therein, said block having its lower corners cut away to permit insertion of the end portions thereof between said lugs and said shank 75 only after said butt has been displaced rearwardly in said yoke to position a part of said shank of reduced vertical dimension above said transverse flange.

In testimony whereof, I have subscribed 80 my name.

GEORGE C. MURRAY.

Certificate of Correction.

It is hereby certified that in Letters Patent No. 1,418,450, granted June 6, 1922, upon the application of George C. Murray, of Chicago, Illinois, for an improvement in "Drawbar Yokes," an error appears in the printed specification requiring correction as follows: Page 4, line 24, claim 11, for the word "hooked" read *hooded*; and that the said Letters Patent should be read with this correction therein that the same may conform to the record of the case in the Patent Office.

Signed and sealed this 11th day of July, A. D., 1922.

[SEAL.]

KARL FENNING,

Acting Commissioner of Patents.
